DRUM ROLLING DEVICE

Mark Owen, Seattle, Wash., assignor to Northern
Stevedores, Inc., Seattle, Wash., a corporation
of Washington

Application July 23, 1941, Serial No. 404,347

8 Claims. (Cl. 294—4)

This invention relates to a stevedoring device, and is particularly intended to facilitate the handling, by rolling, of heavy drums or barrels.

In general it is contemplated to provide a device in the nature of a yoke engageable within the chimes at the opposite ends of the drum, whereby the drum can be pulled, or eased down an incline. Such devices are known, but all those of which I am aware have been complicated and expensive, not sufficiently rugged, and for these and other reasons not suitable to such uses as the handling of heavy oil drums and the like. It is the object of this invention generally to improve such prior devices by making them materially simpler, cheaper, and more rugged, more easily applied and detached, and more convenient in use.

More especially, and as related to convenience, it is an object to provide a device of the general nature indicated, wherein all parts are automatically held by engagement with the drum in position such that the pull on the drum is in a general radial direction or plane, and yet to avoid any rigid engagement with the drum, such as would destroy the flexibility necessary in particular for changing the direction in which the drum is rolling by pulling on one end or the other.

With these and other objects in mind, as will appear from further study of the drawing, specification, and claims, the invention comprises the novel parts, and the novel combination and arrangement thereof, with relation to one another, as shown in the accompanying drawing, and as will be more particularly defined by the claims which terminate the same.

In the accompanying drawing my invention is shown in a form of construction which is at present preferred by me, it being understood, however, that various changes may be made in the form, character, and arrangement of the parts without departure from the spirit of the invention as defined in the claims.

Figure 1 is a perspective view, parts being broken away, showing the invention in use.

Figure 2 is a side elevation of the device, with parts broken away, shown in operative relation to a drum.

Figure 3 is a section transversely through the handle, showing a detail of construction.

Figure 4 is a view similar to Figure 2, showing the device in the position with respect to the drum that it may occupy temporarily for rolling the drum down an incline.

Figure 5 is a view similar to Figure 2, illustrating a modified form of the device.

A drum in the nature of an oil drum is shown by way of illustrating the manner of use of the invention, but of course it will be understood that any style of drum, barrel or cask may be handled by the use of the invention, provided it has a chime projecting beyond its head. Thus the drum 1 is provided with the heads 11 and 12, inset slightly from the ends of the periphery to define the chimes 13 and 14, and peripheral flanges 15 define tracks whereon the drum may roll. In Figure 1 the drum is indicated as rolling along a gangway or ramp 8.

15 In its preferred form the invention is embodied in a yoke of generally U shape, which may be formed of a single piece of spring metal, indicated at 1. Its ends 11 and 12 are spread apart sufficiently that by a little outward forcing they may straddle or encompass the ends of the drum 1, and upon the inner sides of these ends are carried rollers 21 and 22, respectively, which are generally coaxial, which face inwardly, and which engage within the chimes 13 and 14, respectively. 20 While inwardly directed contact members other than rollers may be employed, it will be understood that rollers would normally be employed, and are preferred.

The device thus far described has a certain degree of advantage over prior devices in that it is extremely simple, cheap, convenient, and rugged. With the rollers 21 engaged within the chimes of the drum, the bottom of the U, as indicated at 15, serves as a handle, by which the drum can be pulled along, in the direction of the arrow A (Figure 1), or can be eased down an incline in the opposite direction. However, upon any slackening of the pull the rollers 21 would tend to roll down the chimes toward the bottom, and upon resumption of the pull there would be some interval necessary to take up slack, and some slight shock. The stevedore would not, at all times, have full control over the drum, and accidents might result. It is much preferred, therefore, that the rollers 21 be supported always at an elevation such that they lie generally in a radius through the drum extended through the handle 15.

To the latter end I provide rollers 31 and 32, 30 supported from the yoke by means such as the branches 13 and 14. These branches 13 and 14 are directed somewhat upwardly and inwardly from the corresponding ends 11 and 12, to the end that the rollers 31 and 32 engage the outer periphery of the drum somewhat inwardly from

its ends, and more or less in the top portion of the drum's periphery. Otherwise expressed, and as may be seen in Figure 2, the rollers 31 and 32 are spaced angularly of the drum from the rollers 21, and are also spaced inwardly therefrom, as may be seen in Figure 1. So positioned, they support the rollers 21 at the proper elevation with relation to the center of the drum and the handle 15, so that the rollers 21 never drop down, yet the rollers 21 and 22 are not rigidly clamped in engagement with the inside of the peripheries of their respective chimes.

If the device is to be used upon casks, drums, etc., of widely varying diameters, adjustment of the vertical spacing of the rollers 31, 32 from the rollers 21, 22 may be suitably provided for. Ordinarily it is preferable that different devices be used for widely differing drums, etc.

It is desirable to avoid close confinement or clamping of the chime-engaging rollers with their chimes, as referred to above, for the reason that, in effecting a change of direction as the drum rolls, it is desirable to pull sidewise on the handle 15, in the direction, let us say, of the arrow B, and when this occurs the pull is transmitted to the drum mainly by the roller 22, and it is desirable that the roller 21 move inwardly toward the center of the drum and away from its chime 73. However, to assist further in changing the direction of the drum I provide lugs 17 and 18, supported upon the respective ends 11 and 12 of the yoke, as by welding, but so positioned, each with respect to its chime-engaging roller 21 or 22, that when the roller is engaged within the chime the corresponding lug is spaced some appreciable distance outwardly from the periphery of the drum, as may be clearly seen in Figures 1 and 2. In this way inward movement of the roller 21 is permitted, when the pull on the handle is in the direction of the arrow B, yet the lug 17 will come into contact with the periphery of the drum, and the push through the lug 17 will assist the pull through the lug 17 will assist the pull through the roller 22 in changing the direction of the drum.

Two rollers 31 and 32 have been referred to, and preferably would be employed, but it will be understood, of course, that these typify a contact device (for one only may be employed) or contact devices of any suitable nature, positioned as has already been described.

It will be noted that a tension spring 6 has been shown connected to draw together the ends 11 and 12 of the yoke 1. Such a spring may be employed, if desired, or may be omitted if the spring force of the yoke itself is deemed inadequate.

Likewise I have shown a hand grip 9 located inside the handle 15, and supported therefrom by stiff springs 90 encircling the supporting rivet shanks 91. This affords a shock absorbing connection between the hand grip 9 and the handle 15. Any other suitable shock absorbing arrangement may be employed, or there need be no such shock absorbing connection, so far as the principles of the invention are concerned. Its employment or omission is a matter of choice and convenience.

The device is intended to be used in pulling the drum, in the direction of the arrow A in Figure 1. Sometimes, however, the drums cannot be pulled, as they will tend to roll down an incline and to overrun anyone in front of the drums. By locating the rollers 31 and 32 angularly from the rollers 21 and 22 by a sufficiently

small amount it is possible, when the drum tends to overrun the puller, to stand aside, swing the handle over the drum, and then to use the handle to hold back the drum, the parts then being in the position shown in Figure 4.

Stevedores are accustomed to push the drums, and while the use of the device in this manner is not recommended, it is possible to employ the device for pushing the drums, by providing a third set of rollers 41 (as seen in Figure 5) carried upon a branch 19, supported upon the yoke and spaced angularly from the chime-engaging rollers 21 and 22, but at the opposite side of the yoke from the rollers 31 and 32. It should be noted that the three rollers 21, 31 and 41 are so located that never do more than two such rollers at any given end of the drum engage the drum. For pushing, the rollers 31 and 41 would engage the drum, and the roller 21 would be moved inwardly away from contact with the inside of the chimes. For pulling, the roller 21 would engage the chime, and probably the roller 31, but the roller 41 would then be lifted from engagement with the periphery of the drum. This avoids any binding contact with the drum, or clamping action, and gives greater flexibility and freedom in use, particularly for effecting turning of the direction of rolling of the drum.

What I claim as my invention is:

1. A drum roller comprising two connected arms urged together but capable of being spaced apart to encompass the ends of a drum, a roller mounted upon each such arm in planes generally parallel to the drum's heads, and engageable within the chimes, a handle connected to said arms and spaced outwardly of the drum, and a contact member supported from the arms in position to ride upon the top of the drum, and thereby to support the rollers approximately in a radius of the drum extended through the handle.

2. A drum roller comprising two connected arms urged together but capable of being spaced apart to encompass the ends of a drum, a roller mounted upon each such arm in planes generally parallel to the drum's heads, and engageable within the chimes, a handle connected to said arms and spaced outwardly of the drum, and a lug upon each arm, spaced from the drum's periphery when the rollers are engaged within the chimes, but sufficiently close to be engageable therewith by a sidewise pull upon the handle, thereby to assist the opposite roller in changing the drum's direction, as it rolls.

3. A drum roller comprising two connected arms urged together but capable of being spaced apart to encompass the ends of a drum, a roller mounted upon each such arm in planes generally parallel to the drum's heads, and engageable within the chimes, a handle connected to said arms and spaced outwardly of the drum, and a pair of rollers supported one from each of the arms, spaced inwardly from the ends of the drum, and spaced angularly from the chime-engaging rollers to rest upon the top of the drum, and thereby to position the chime-engaging rollers approximately in a radius of the drum extended through the handle.

4. A drum roller comprising two connected arms urged together but capable of being spaced apart to encompass the ends of a drum, a roller mounted upon each such arm in planes generally parallel to the drum's heads, and engageable within the chimes, a handle connected to said arms and spaced outwardly of the drum, a pair of rollers supported one from each of the arms,

spaced inwardly from the ends of the drum, and spaced angularly from the chime-engaging rollers to rest upon the top of the drum, and thereby to position the chime-engaging rollers approximately in a radius of the drum extended through the handle, and a second pair of rollers supported one from each of the arms, spaced inwardly from the ends of the drum, and angularly from the chime-engaging rollers, but at the opposite side of the arms from the top-engaging rollers, to engage the lower rear periphery of the drum, for pushing.

5. A drum roller comprising a yoke of spring metal formed in U-shape, with the ends of its arms spread to encompass, when expanded, the ends of a drum, two rollers, generally coaxial, one mounted upon each such end, and engageable within the chime of the drum by the inwardly-acting spring force of the arms, the bottom of the U constituting a handle for pulling the drum, an inwardly directed branch rigid with each arm, and a roller upon each branch in position to ride upon the top of the drum, distant from the first rollers, and thereby to support said chime-engaging rollers approximately in a radius of the drum extended through the handle.

6. A drum roller comprising a yoke of spring metal formed in U-shape, with the ends of its arms spread to encompass, when expanded, the ends of a drum, two rollers, generally coaxial, one mounted upon each such end, and engageable within the chime of the drum by the in-

wardly-acting spring force of the arms, the bottom of the U constituting a handle for pulling the drum, and a lug upon each arm, spaced from the drum when the rollers are engaged with the chimes, but engageable therewith to assist in changing direction of the drum, by a sidewise pull upon the handle.

7. A drum roller comprising two connected arms urged together but capable of being spaced apart to encompass the ends of a drum, a roller mounted upon each such arm in planes generally parallel to the drum's heads, and engageable within the chimes, a handle connected to said arms and spaced outwardly of the drum, a contact member supported from the arms in position to ride upon the top of the drum, and thereby to support the rollers approximately in a radius of the drum extended through the handle, and shock-absorbing means interposed between the handle and the rollers.

15 8. A drum roller comprising a yoke of spring metal formed in U-shape, with the ends of its arms spread to encompass, when expanded, the ends of a drum, two rollers, generally coaxial, one mounted upon each such end, and engageable within the chime of the drum by the inwardly-acting spring force of the arms, the bottom of the U constituting a handle for pulling the drum, a hand grip disposed inside the handle, and shock 20 absorbing means acting therebetween.

MARK OWEN.
